UNITED STATES PATENT OFFICE

WILLIAM E. RAWLINGS, OF SANTA CLARA COUNTY, CALIFORNIA

FLOAT

Application filed August 27, 1930. Serial No. 478,105.

This invention relates to a float, and particularly to a means for propelling the same.

It is one object of the invention to provide a float that will comfortably accommodate several persons, providing both a seat and foot rest therefor, and one that will permit collapsing of the foot rest for storing the device or for permitting it to be moved more rapidly over the water.

It is also an object to provide a device of the character indicated provided with a propelling means detachably mounted thereon, and to provide a propelling means that will be exceptionally economical to manufacture, strong, durable, and highly efficient in its practical application.

In the drawings:

Figure 1 is a side elevation of a device embodying my invention.

Figure 2 is a section on line 2—2 of Figure 1.

Figure 3 is a detail of one of the catches for holding the foot rest in position.

Figure 4 is an enlarged section on line 4—4 of Figure 2.

In the embodiment of the invention shown, 1—1 indicates two spaced parallel buoyant members, and 3 indicates a seat member disposed midway therebetween, with foot rests 30 indicated at 4—4.

The foot rests and the seat are supported on the buoyant members by means of a pair of rods as 5, each rod having its ends overlying the two members 1—1 and held in place 35 by suitable means as staples 6 whereby to permit a pivotal movement of the rod. The intermediate portion of the rod is shaped in general like the letter W with seats at 7 for foot rests 4, and a middle seat at 8 for the 40 seat member 3.

When in use the rods are held in the position shown by any suitable means as a spring catch 9, and when the rods 5 and foot rests 4 are swung up into a position parallel with 45 the seat to permit the device to be moved rapidly through the water they are held by spring catches at 10.

The device is propelled by a device comprising a handle 11 passing through a slot 50 12 in seat 3 and pivotally mounted thereon

by a removable transverse pin shown at 13. The portion of the propelling means in the water comprises a rectangular frame 14 having opposed vertical grooves 15 in its side parts, and a series of slats 16 horizontally pivoted therein to swing as shown in Figure 4. When swung as indicated by arrow 17 water passes freely therethrough, but when swung as indicated by arrow 18 the slats swing into a vertical plane overlapping as at 19 and prevent passage of the water whereby to impart a forward impulse to the float.

It is to be understood, of course, that while I have herein shown and described but one specific embodiment of the invention, changes in form, construction, and method of assembly and operation may be made within the scope of the appended claim.

I claim:

A float comprising a plurality of spaced 70 parallel buoyant members, W shaped suspension bars pivotally mounted thereon, a seat member and foot rest members mounted on the bars, means for locking the bars in a given position, and means for propelling 75 the float.

WILLIAM E. RAWLINGS.
